Primary Examiner — Brett Miller*Assistant Examiner* — Suzanne E Tisdell(74) *Attorney, Agent, or Firm* — Schott, P.C.(57) **CLAIM**

The ornamental design for the decklid panel for an automobile, as shown and described.

DESCRIPTION

FIG. 1 is a front elevation view of a decklid panel for an automobile of the present invention;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a perspective view thereof; and,

FIG. 8 is another perspective view thereof.

Any broken lines are provided for the purpose of illustrating environmental structure(s) and form no part of the claimed design.

1 Claim, 5 Drawing Sheets(56)
